UNITED STATES PATENT OFFICE.

CHARLES A. BACKSTROM, OF PHILADELPHIA, PENNSYLVANIA, ASSIGNOR TO INTERNATIONAL POWER GENERATOR COMPANY, A CORPORATION OF DELAWARE.

METHOD OF UTILIZING PRODUCTS OF COMBUSTION AND APPARATUS THEREFOR.

974,458.

Specification of Letters Patent.

Patented Nov. 1, 1910.

Application filed September 15, 1908, Serial No. 453,106. Renewed April 7, 1910. Serial No. 554,044.

To all whom it may concern:

Be it known that I, CHARLES A. BACKSTROM, a citizen of the United States, residing in the city and county of Philadelphia, 5 State of Pennsylvania, have invented a new and useful Apparatus for Utilizing Products of Combustion in Combination with other Suitable Gases, of which the following is a specification.

- 10 My present invention relates to a novel construction of an apparatus for utilizing the products of combustion in combination with other suitable gases, such as for example steam.
- 15 The object in view is to devise a form of construction or means by which all the products in a generator or boiler such as a mixture of steam, gases of combustion, air or other fluids capable of absorbing and 20 storing heat will be delivered directly to a prime-mover at a suitable pressure and temperature and discharged therefrom after all of the available heat energy has been extracted or converted into useful 25 work. With such objects in view I provide an apparatus wherein the casing surrounding the generator has a water jacket to which feed water at a comparatively low 30 temperature is fed, thus reducing the temperature differences to a minimum between the generator proper and the surrounding atmosphere. The importance of this feature will be readily apparent to those skilled 35 in this art since the temperature of the generator proper is enormously high and the losses would be enormously great without interposing between the generator proper and the atmosphere a heat absorbing medium which is continuously fed into the generator proper as the temperature of the heat 40 absorbing medium rises, thereby maintaining a low temperature of the outer wall of the water jacket and thus avoiding all losses from radiation to the atmosphere.
- 45 It is well known in the art that an engine operating with steam or one operating with the products of combustion, such as an internal combustion engine, has a comparatively low thermal efficiency, that is to say, 50 only a small fraction of the heat energy of the fuel is converted into useful work.

For the purpose of illustration, I have shown in the accompanying drawings one embodiment of my invention which has

been found in practice to give satisfactory 55 and reliable results, although it is to be understood that the various instrumentalities of which my invention consists can be variously arranged and organized and that my invention is not limited to the precise arrangement and organization of these instrumentalities as herein set forth.

Figure 1 represents a side elevation of an engine and generator by the employment of which my method may be carried out. Fig. 65 2 represents a sectional elevation of the generator in detached position.

Similar numerals of reference indicate corresponding parts in the figures.

Referring to the drawings, 1 designates 70 a Westinghouse engine of the Junior type in which the valve actuating mechanism has been adapted to operate pumps 2 and 3 one for compressing air to a desired pressure and the other as a feed pump to supply the 75 apparatus with water or other heat absorbing medium. The generator 4 is mounted directly on the engine in close proximity to the steam chest 5 and the motive fluid from the generator passes through a conduit 6 80 downward into the engine. The generator consists of a casing 7 which is provided with an annular space or water jacket 8 and an internal boiler or evaporating means 9 consisting of an outer shell 10 to which is secured two heads 11 and 12 perforated to receive a number of tubes 13 in the usual manner. A burner 14 of any suitable construction is provided to which a liquid or gaseous fuel is delivered through the conduit 15 90 and compressed air is delivered through the conduit 16. The mixture is ignited by means of the sparking device 17 and burns continuously under a constant pressure as long as the air and fuel are admitted. Water is supplied at 18 and absorbs while remaining in the annular space 8 a certain amount of heat. The water passes from the chamber 8 through ports 19 into the boiler 9 and is evaporated forming steam which escapes through ports 20 mixing with the products of combustion that flow upward through the tubes 13 into mixing chamber 21 from whence the mixture passes directly into the engine through port 22 and conduit 6 and having performed its mission by expanding against the resisting pistons is exhausted to the atmosphere.

From the above it will be readily seen that all the heat energy resulting from the combustion of fuel is utilized save that amount which is lost by radiation due to the slight 5 temperature differences and that due to the exhaust pressure.

The operation is as follows:—Fuel is introduced into the conduit 15 and air under pressure is introduced into the conduit 16 10 and the mixture passes to the burner 14 and is ignited by means of any suitable mechanism such as the sparking device 17. The products of combustion flow through the tubes or conduits 13 in close proximity to 15 the heat absorbing medium which would preferably be water and a certain amount of heat is absorbed by the water thereby producing steam which escapes through ports 20 and mixes with the products of combustion 20 so that the mixture of steam and products of combustion enters the engine through port 22 and conduit 6.

It is essential in a device of this character to provide some means for absorbing the 25 heat which would otherwise be lost due to radiation, which on account of the small cubic capacity of the device and the high temperature would be a large percentage of the total heat units available for useful 30 work, thus rendering the apparatus impractical for commercial purposes. By the provision of a heat absorbing medium such as water, surrounding the generator proper, and which is introduced directly into the 35 generator the losses due to outside radiation are reduced to such an extent that they may be entirely ignored and a device will be produced in which practically all the heat evolved from the consumption of the 40 fuel is converted into useful work.

It has been found in practice that the fuel consumption per horse power hour is substantially one-third to one-half as compared with other types heretofore employed.

45 It is to be understood that I am not limited to the means herein shown and described to carry out my invention but that these simply illustrate one manner in which my method of utilizing all the products of a 50 boiler or generator may be applied to an ordinary engine.

Having thus described my invention, what I claim as new and desire to secure by Letters Patent, is:—

55 1. In a generator, means for feeding fuel, means for feeding air, a burner to which the

commingled fuel and air are fed, a water jacket, a boiler independently supported in said jacket and located in the heat zone of the burner, said boiler having tubes through 60 which the products of combustion pass and having ports intermediate the discharge end of said tubes through which steam may pass to mix with products of combustion passing through said tubes and around said boiler, 65 and said water jacket communicating with said boiler.

2. In a generator, means for feeding fuel, means for feeding air, a burner to which the commingled fuel and air is conducted, a 70 water jacket, and a boiler independently supported in said jacket, surrounded thereby, and located in the heat zone of the burner, said boiler having tubes through which the products of combustion may pass and hav- 75 ing ports surrounding the discharge ends of said tubes through which products of combustion may pass to mix with the steam issuing from said ports and the products of combustion passing around said boiler, and said 80 water jacket communicating with said boiler.

3. In a generator, a water jacket, a boiler independently supported therein to permit products of combustion to completely surround said boiler; said boiler having a plurality of open ended tubes through which products of combustion may pass, and provided with ports surrounding the discharge 85 ends of said tubes to permit steam to mix 90 with the products of combustion passing through the tubes and around the boiler, a burner carried by the water jacket, means for feeding fuel, and means for feeding air, and said water jacket completely surround- 95 ing the sides and bottom of said boiler.

4. In a steam generator, a boiler having a plurality of open ended tubes to permit passage of products of combustion, and provided with ports between the tubes for escape of steam to cause an intimate commingling of the steam and products of combustion, there being a common chamber for the steam and products of combustion wherein the mixing takes place, and a source of heat 100 for the boiler, said source of heat operating 105 for a pressure higher than atmospheric pressure.
